US0D1026889S

(12) **United States Design Patent** (10) Patent No.: **US D1,026,889 S**
 (45) Date of Patent: ** May 14, 2024

(54) **DISPLAY STAND BASE WITH SPEAKER**

(71) Applicants: **K-Tronics (Suzhou) Technology Co., Ltd.**, Jiangsu (CN); **BOE TECHNOLOGY GROUP CO., LTD.**, Beijing (CN)

(72) Inventors: **Jiahong Jiang**, Beijing (CN); **Min Chen**, Beijing (CN)

(73) Assignees: **K-TRONICS (SUZHOU) TECHNOLOGY CO., LTD.**, Jiangsu (CN); **BOE TECHNOLOGY GROUP CO., LTD.**, Beijing (CN)

(**) Term: **15 Years**

(21) Appl. No.: **29/678,652**

(22) Filed: **Jan. 30, 2019**

(30) **Foreign Application Priority Data**

Oct. 31, 2018 (CN) 201830612345.1

(51) LOC (14) Cl. **23-04**

(52) U.S. Cl.

USPC **D14/209.1**; D14/172; D14/447; D14/252

(57) **CLAIM**

The ornamental design for a display stand base with speaker, as shown and described.

DESCRIPTION

FIG. 1 is a front view of a display stand base with speaker; FIG. 2 is a rear view thereof; FIG. 3 is a left view thereof; FIG. 4 is a right view thereof; FIG. 5 is a top view thereof; FIG. 6 is a bottom view thereof; FIG. 7 is a perspective view thereof; and, FIG. 8 is a front view of the display stand base with speaker shown in a state of use.

The broken lines illustrate portions of the display stand base with speaker that form no part of the claimed design. Additional broken lines in FIG. 8 depict environment subject matter and form no part of the claimed design.

1 Claim, 4 Drawing Sheets
